US00D931749S

(12) **United States Design Patent** (10) Patent No.: **US D931,749 S**
(45) Date of Patent: **** Sep. 28, 2021**

(54) **CARBON MONOXIDE DETECTOR**

(71) Applicant: **Yunlong Zhong**, Henan Province (CN)

(72) Inventor: **Yunlong Zhong**, Henan Province (CN)

(**) Term: **15 Years**

(21) Appl. No.: **29/705,079**

(22) Filed: **Sep. 10, 2019**

(51) LOC (13) Cl. **10-05**

(52) U.S. Cl.

USPC **D10/106.5**; D10/81

(58) **Field of Classification Search**

(57) **CLAIM**

The ornamental design for a carbon monoxide detector, as shown and described.

DESCRIPTION

FIG. 1 is a front perspective view of a carbon monoxide detector, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures illustrate portions of the carbon monoxide detector that form no part of the claimed design.
